(57) **CLAIM**

The ornamental design for a segmented saw blade, as shown and described.

DESCRIPTION

Our invention is a saw blade having a segmented, abrasive cutting rim, substantially shown in FIGS. 1-3.

FIG. 1 is a top plan view of a saw blade showing our new design incorporating different gullet lengths and shapes, with some non-parallel gullets.

FIG. 2 is a cross-sectional view along line A—A of FIG. 1; and,

FIG. 3 is a side elevation view of FIG. 1.
